MULTIPLE CONTACTOR

Joseph F. Frese, Baltimore, Md., assignor to The Monitor Controller Company, Baltimore, Md., a corporation of Maryland

Application February 5, 1945; Serial No. 576,313

5 Claims. (Cl. 200—166)

1

My invention relates broadly to high frequency electrical switches and more particularly to an improved construction of radio frequency contactor for high frequency electrical switches.

One of the objects of my invention is to provide an improved contactor for radio frequency switches having a high degree of electrical and mechanical efficiency.

Another object of my invention is to provide a construction of radio frequency contactor for high frequency switches comprising a multiplicity of resilient strip members of progressively increasing lengths united at one end and having contact projections of uniform length at the opposite ends disposed in coacting relation for establishing progressive connection with a switch contactor.

Another object of my invention is to provide a construction of radio frequency contactor consisting of a multiplicity of laminations secured at one end and free to move in a fan-like spread at their opposite ends as said strip members progressively establish connection with a coacting contact for establishing a multi-surface connection for radio frequency currents.

Still another object of my invention is to provide a contactor system for radio frequency currents in which a large surface area is provided for carrying radio frequency currents between circuit terminals through a multiplicity of progressively closable contact elements.

Still another object of my invention is to provide an improved method of applying highly conductive terminal elements to laminated contact strip members arranged to be secured together at one end and free for progressive displacement at their opposite ends for progressively closing a high frequency electrical circuit with respect to a movable contactor.

Other and further objects of my invention reside in the construction of a laminated contact system for radio frequency currents as set forth more fully in the specification hereinafter following by reference to the accompanying drawings, in which:

Figure 1 is a side elevational view of a high frequency switch equipped with a radio frequency contactor embodying my invention; Fig. 2 is an enlarged fragmentary elevational view showing a movable contactor operative between two of the radio frequency contact devices of my invention; Fig. 3 is a front elevational view of the multiple contactor of my invention; Fig. 4 is a side elevational view of the multiple contactor of my invention; Fig. 5 illustrates the manner of applying a contact surface to one of the contact strips in the contactor of my invention; Fig. 6 is a cross-sectional view showing the contact surface applied to the contact strip; Fig. 7 is a transverse sectional view through the contact strip

2

and contacting surface taken on line 7—7 of Fig. 6; Fig. 8 is a cross-sectional view of a movable contactor moving in coacting relation to the multiple contactor of my invention for progressively closing a circuit through opposite circuit terminals; Fig. 9 is a view similar to the view shown in Fig. 8 but illustrating the progressive circuit closing operation in a more advanced stage; Fig. 10 shows the progressive operation of 10 the contactor and the multiple contactor completed and the high frequency contact established; Fig. 11 is a transverse sectional view taken through the position of support for the multiple contactor on line 11—11 of Fig. 8; Fig. 12 is a 15 fragmentary elevational view of the movable contactor employed in association with the multiple contactor of my invention; Fig. 13 is a transverse sectional view taken on line 13—13 of Fig. 8; Fig. 14 is a plan view of the guide for the laminated contactor; Fig. 15 is a longitudinal sectional view taken through the guide on line 15—15 of Fig. 14; and Fig. 16 is a transverse sectional view through the guide on line 16—16 of Fig. 14.

Referring to the drawings in detail the electrical contact system is composed of a plurality of relatively narrow strip-like members that I have indicated by reference characters 1, 2, 3, 4, 5, 6, 7, 8 and 9 stacked in superimposed relation and secured together at one end by solder. For purposes of explaining my invention, I have indicated the solder spread into layers 10 intermediate the strips. It will be understood, however, that the solder layers may, in fact, not actually constitute separators for the strips but merely provide junction means for the edges of the superimposed strips for binding the strips as a unit at the ends thereof. The ends of the strips as thus united are drilled as represented at 12 for the passage of a securing screw 14 having a screw-slotted head 14a and extending through a washer member 15 bearing against a channel shaped guide plate member 16 which has a flat portion that bears against the exterior surface of the first of the resilient strips of the multiple contact device as indicated at 1 and a pair of parallel extending side portions 16a and 16b. The strips constituting the multiple contact system are of differing thicknesses, the strips 1 and 2 forming the rear limit of the contact system 20 having greater thickness than the strips 3, 4, 5, 6, 7, 8 and 9 which are of shorter effective length. The several strips thus secured together at one end are free to spread in fan-like arrangement as indicated more particularly in Figs. 9 and 10. 25 The top limiting strip 9 of the multiple contact system abuts directly against an abutment strip 17 which is confined between the side portions 16a and 16b of the channel shaped guide plate member 16 and extends in surface contact with 30 the angle member 18 into which the securing

screw 14 is screw-threaded. The channel shaped member 16 has the sides 16a and 16b thereof spaced from opposite edges 18a and 18b of the angle member 18 for allowing the contact strips to freely move in a fan-like spread, without appreciable transverse displacement.

The angle member 18 is secured to any suitable supporting surface such as the insulation material represented at 18 by means of screw member 20 which extends through the insulation material 19 and is engaged by means of screw threads in the angle member 18. The angle member 18 is disposed at a predetermined acute angle with respect to the supporting surface 19 to provide for the mounting of the multiple contact in such manner that the separable parts of the contact system may be progressively contacted for progressively closing the electric circuit. As illustrated in Figs. 1, 2 and 10, for example, the circuit through the high frequency contact is shown completed after the contact face 21 of the contactor arm 22 has moved to its limit of travel. In the position illustrated in Figs. 1, 2 and 10 the multiplicity of contact members are all displaced away from the channel shaped member 17 by movement of the contact face 21 into contacting relation to the separate contact members carried by the separable leaf springs 1-9 inclusive.

The contact members which are carried by the separable leaf springs 1-9 each consist of strip-like members represented, for example, at 23 having a large surface area and high electrical conductivity. Sheet silver is generally used to obtain low resistivity and high electrical conductivity for the high frequency currents. In Fig. 5 I have shown the sheet-like member 23 bent upon itself in substantially U-shaped section with the sides thereof sufficiently spaced to enable the contact member to be slipped over the end of the spring strip indicated, for example, by reference character 1. The sheet-like member 23, after it is moved into the position illustrated in Fig. 5, is pressed into intimate engagement with the strip 1 as represented in Figs. 6 and 7. The strip 1 is apertured at 1a and 1b at spaced intervals transversely of the strip and these apertures serve to receive protuberances indicated at 23a, 23b, 23c and 23d forced from the material of the sheet-like member 23 under pressure directed thereagainst in the direction of arrows 24. In addition to the interlocking engagement between the sheet-like member 23 and the strip 1 provided by the protuberances 23a, 23b, 23c and 23d, I provide a solder connection which takes the form of a thin film indicated generally at 23e which spreads between the juncture of the exterior faces of the strip 1 and the interior faces of the sheet-like member 23.

A similar arrangement of contact faces is provided for each of the resilient strips forming the multiple contact system. Each of the strip-like members are bent at right angles to the place thereof immediately below the edge extremities of the sheet-like strips represented, for example, at 23 so that the high frequency contact surface of each sheet-like member is directed in a plane which is substantially normal to the plane of the resilient strip-like member which carries the sheet-like member. The ends of all of the strip-like members are bent uniformly, that is, to the same depth so that each of the contacts have the same effective length. The sheet-like members carried by the associated strip-like members are represented at 24, 25, 26, 27, 28, 29, 30 and 31 and constituting the multiple contacts are each inde-

pendently displaceable under the pressure exerted by contact 21 as it moves into engagement with the multiple contacts. Inasmuch as large surface area for the distribution of high frequency currents is desirable for promoting efficiency, the multiple contact system of my invention ideally carries out the maintenance of high electrical conductivity and low resistivity.

As illustrated in Fig. 8 sheet-like members 23, 24 and 25 constitute the initial contacting abutments for the contact surface 21 as the switch arm 22 is shifted angularly toward the multiple contactor. As the swinging of the switch arm continues contact surface 21 progressively establishes connection with surfaces of the sheet-like members 26, 27, 28, 29, 30 and 31. In Fig. 9, for example, the switch arm 22 has moved to a position in which leaf springs 1, 2 and 3 carrying sheet-like members 23, 24 and 25 have each been further displaced and sheet-like members constituting contact surfaces 26, 27, 28 and 29 carried respectively by strips 4, 5, 6 and 7 have progressively established contact with contact surface 21.

As the switch arm 22 continues to move in the direction of the arrow 32 the sheet-like members 30 and 31 carried by strips 8 and 9 have the electrical circuit completed therethrough with contact surface 21. It will be observed that the fan-like strips change in their spacial relation as the switch arm 22 moves contact surface 21 into engagement with the sheet-like members finally effecting displacement of the entire group of multiple strips away from the flat strip 17 as illustrated in Fig. 10. Thus a yielding abutment is provided for the movable contactor and a large surface area for the flow of high frequency currents is assured.

On the return stroke of the switch arm 22 the multiple contactor just described is released and the separation between the contact surface 21 and the sheet-like members 31, 30, 29, 28, 27, 26, 25, 24 and 23 are separated from surface contact with contact surface 21 in the reverse progressive order in which the connection was initially established. As switch arm 22 continues its reverse movement the contact surface 33 carried thereby is brought into registration with the oppositely disposed contact member which I have represented at 34. The contact surface 33 is secured to the switch arm 22 through a rivet connection 35 which also secures the contact surface 21 in position. In addition there is a rivet 36 for securing the lower end of contact surface 33 in position whereby contact surface 33 is presented to the progressive multiple contactor represented at 34. Tubular switch arm 22 is flattened out of round and is bent on axes extending at obtuse angles to each other to present the contact surfaces 21 and 33 to the echelon contacts.

The multiple contactor 34 is constructed in a manner similar to the multiple contactor heretofore described in that contactor includes a multiple number of contact surfaces which I have represented at 35, 36, 37, 38, 39, 40, 41 and 42 which become progressively effective in establishing connection with the contact surface 33 in the order named as the switch arm 22 moves about its pivot into connection with the contactor. The contactor 34 includes a multiplicity of resilient strips stacked one with respect to the other in a manner identical to the arrangement heretofore explained and fastened at their ends shown at 43 and secured by means of screw 44 to the angle 45. A flat abutment strip 45 provided in surface contact with angle 45 and between the

side portions of the channel member 50 serves as an abutment for the resilient strips. Channel member 53 is shaped in a manner similar to channel member 16 and functions as a guide for the strips of the multiple contactor 34. Angle 45 is secured by suitable means such as bolt member 47 to the insulated structure 19 in the required angular position to properly present the multiple contactor to the movable contacts as they shift angularly between the contactors.

Electric current terminals are provided for the multiple contactors as represented at 48 and 49 suitably insulated through the support 19.

In Fig. 1 I have illustrated one form of magnetic actuator which may be employed for the switch system of my invention. The magnetic actuator shown is similar to the actuator illustrated in my Letters Patent 2,125,436, granted August 2, 1938, for High frequency electrical switch and electromagnetic actuating means therefor. It is sufficient to indicate herein that solenoid 50 operates to move armature 51 which is pivoted at 52 and which carries the operating switch arm 22 as shown. Details of the switch construction are immaterial and various forms of switch may be used to operate in coaction with the multiple contactor of my invention.

The multiple contactor of my invention has been found to be highly practical in construction and production and very efficient in operation inasmuch as large surface area is provided for the flow of high frequency currents.

While I have described my invention in one of its preferred embodiments, I desire that it be understood that modifications may be made and no limitations upon my invention are intended other than may be imposed by the scope of the appended claims.

What I claim and desire to secure by Letters Patent of the United States is as follows:

1. A multiple contactor comprising, a multiplicity of resilient strip members stacked face to face and united at one end and free to move in a fan-like spread at their opposite ends as said strip members are moved toward or away from an abutting contact, said resilient strip members having their ends bent at an angle to the surface thereof and having a pair of symmetrically arranged spaced apertures at said bent ends, said sheet-like contact members enveloping said bent ends and being extruded into the pair of symmetrically arranged apertures in the bent ends of said strip members for forming contacts operative to establish progressive connection with said fixed contact, said contact members each extending in substantially parallel planes substantially normal to the face of said strip members.

2. A multiple contactor comprising, a multiplicity of resilient strip members of progressively varying length stacked face to face and united at one end and free to move in a fan-like spread at their opposite ends as an abutting contact establishes contacting relation therewith, contact members carried by said strip members in echelon arrangement, the echelon arrangement varying from a minimum projection adjacent the end of the multiple contactor to a maximum projection displaced from the end of the multiple contactor for progressively establishing connection with an abutting contact, and said resilient strip members varying from minimum resiliency in the

longest of said strip members to maximum resiliency in the shortest of said strip members for controlling the displacement of said multiple contactor.

3. A multiple contactor comprising a multiplicity of resilient strip members of progressively varying length stacked face to face and united at one end and free to move in a fan-like spread at their opposite ends as an abutting contact establishes contacting relation therewith, contact members carried by said strip members in echelon arrangement, the echelon arrangement varying from a minimum projection adjacent the end of the multiple contactor to a maximum projection displaced from the end of the multiple contactor for progressively establishing connection with an abutting contact, and said resilient strip members varying from maximum thickness in the longest of said strip members to minimum thickness in the shortest of said strip members for controlling the displacement of said multiple contactor.

4. A multiple contactor comprising a multiplicity of resilient strip members stacked face to face, each of said strip members being turned at one end thereof and projecting for a uniform distance therefrom and carrying contactors free for displacement in a fan-like spread with respect to a contact surface and a channel shaped member having side portions extending on opposite sides of said resilient strip members throughout the thickness of the stacked strip members for preventing appreciable edgewise displacement of said strip members while permitting the unrestricted fan-like spreading thereof for effecting a multiplicity of spaced electrical connections with the contact surface.

5. A multiple contactor comprising a multiplicity of aligned resilient strip members stacked face to face, each of said strip members being turned at one end thereof and projecting for a uniform distance therefrom and carrying contactors free for displacement in a fan-like spread with respect to an abutting contact surface and a guide member constituting a plate secured adjacent the confined ends of said resilient strip members, said plate having a pair of coextensive projecting portions extending adjacent the opposite edges of said strip members and sufficiently spaced therefrom to allow said members to move in an unrestricted fan-like spread while maintaining their aligned relation throughout the displacement in a fan-like spread.
